UNITED STATES PATENT OFFICE.

ALEX BERNSTEIN, OF CHICAGO, ILLINOIS.

NECKBAND FOR SHIRTS.

1,375,350.

Specification of Letters Patent. Patented Apr. 19, 1921.

Application filed February 3, 1919. Serial No. 274,779.

To all whom it may concern:

Be it known that I, ALEX BERNSTEIN, a citizen of the United States, and a resident of the city of Chicago, in the county of Cook and State of Illinois, have invented certain new and useful Improvements in Neckbands for Shirts; and I do hereby declare that the following is a full, clear, and exact description of the same, reference being had to the accompanying drawings, and to the numerals of reference marked thereon, which form a part of this specification.

Haberdashers and dealers in men's furnishings are usually required to carry complete lines of shirts of a number of different patterns, colors and materials, and in order to supply the trade with the desired size of shirt asked for, it is imperative that eight or ten different sizes be carried in stock for each particular pattern or different color of a pattern. This requirement, of course, necessitates the carrying of an exceptionally large stock of shirts, since a person wishing to purchase a shirt of a certain color and pattern must have his particular size so that his collars will fit on the neck band of the shirt. Due to the stiff lining of shirt neck bands practically only one size of collar is permitted to be conveniently fitted on a shirt neck band. If a collar smaller than the neck band of a shirt is buttoned on the large shirt band considerable inconvenience is occasioned for the reason that the larger shirt band must first be slit, cut, or folded to receive the smaller collar thereon. Even after the smaller collar is secured on a larger shirt band, the shirt band which is stiff acts to irritate a person's neck and furthermore doubles on itself and becomes bulky within the collar.

This invention relates more particularly to an improved type of shirt neck band, wherein portions of the neck band lining or stiffening are omitted to afford flexible sections in the neck band, permitting collars of different sizes to be conveniently worn on a particular sized shirt, and thereby permitting haberdashers to materially reduce the stock of shirts and still be able to supply the trade with shirts adaptable for collars of a plurality of different sizes.

It is an object of this invention to construct a garment collar band adapted to conveniently permit collars of different sizes to be worn therewith.

Another object of the invention is the

construction of a shirt neck band having flexible sections permitting the neck band to be easily adapted for use with different sized collars.

A further object of the invention is the construction of a shirt neck band having flexible portions therein formed by omitting portions of the neck band lining so that a collar ordinarily too small for a regular shirt of a particular size can be easily worn with a shirt of the same size having the improved neck band thereon.

It is an important object of this invention to provide an improved shirt neck band adapted to be assembled and then secured to a shirt by a single operation, and when in place permitting collars smaller than the size of the neck band to be conveniently worn thereon with comfort.

Other and further objects of this invention will be apparent from the disclosures in the specification and drawings.

The invention (in a preferred form) is illustrated in the drawings and hereinafter more fully described.

On the drawings:—

Figure 1 is a perspective view of a shirt neck band embodying the principles of this invention, and shown attached to a shirt, of which a fragmentary portion only is shown.

Fig. 2 is a fragmentary portion of one side of the neck band shown in elevation and disclosing one of the flexible sections forming a part of the neck band.

Fig. 3 is a section taken on line 3—3, of Fig. 2.

Fig. 4 is a section taken on line 4—4, of Fig. 2.

As shown on the drawings:—

The reference numeral 1, indicates a garment or shirt having secured thereon by stitching or other suitable means an improved type of neck or collar band comprising the elements of this invention and embracing an outer strip or band 2, and an inner strip or band 3, both of which are secured together by stitching along the upper and end edges in the customary manner.

Disposed between the outer and the inner strips of cloth 2 and 3, at the rear portion and in each of the end portions of the neck band, are lining or stiffening sections 4, which are stitched or otherwise secured in position at 5, to hold the same in place to form padded or stiffened sections. As

clearly shown in Figs. 1 and 3, reduced flexible thinner portions or sections 6, without lining or stiffening, are formed on opposite sides of the neck band between each of the 5 lined thicker front end portions of the neck band and the lined thicker rear portion thereof. Button holes 7, are provided in the neck band at the rear middle portion and at the front ends in the customary manner.

10 The improved collar or neck band may be made of any desired material and the three pieces of lining or stiffening may be secured in the respective positions as hereinbefore described, to provide the unstiffened or 15 flexible sections 6, therebetween. The neck band is adapted to be assembled or formed complete with the button holes formed therein, to permit the neck band at the proper time during the progress of the making 20 of a shirt to be attached in place to the neck margin of the shirt 1, by stitching or other suitable means, with a single operation. As shown in Fig 4, the neck margin of the shirt 1, is inserted into the lower 25 open portion of the assembled neck band between the outer and inner cloth strips 2 and 3, and between the layers of lining or stiffening 4.

It will of course, be understood that any 30 number of flexible unlined sections 6, may be provided in the neck band, and further that said flexible sections may be disposed in any convenient position other than at the sides of the neck band as shown and de- 35 scribed.

A shirt of a given size which is provided 40 with the improved type of adjustable neck band, is adapted to readily have buttoned onto the neck band not only a collar of the proper size for the shirt but collars of smaller sizes.

On the ordinary shirt of a given size a collar of the same size as the shirt is usually used, and sometimes collars of perhaps a 45 quarter or half size larger may be used on the shirt. Collars of smaller sizes than the shirt are, however, not adapted to be worn without considerable trouble in securing the smaller collars in place on the shirt neck 50 band, and without much inconvenience and uncomfortableness in wearing. This is due to the fact that ordinarily the neck band of a shirt is equally stiff all the way around so that no part thereof is adapted to give way 55 or fold to permit a smaller sized collar to fit around the neck band. When a smaller collar is finally secured to a larger shirt neck band, part of the stiff neck band is bent or folded inwardly and usually forms a rib

or bulky projection which is not only very 60 uncomfortable but oftentimes acts to irritate the neck of the person wearing the shirt and collar.

Collars of both larger and smaller sizes 65 may be used with the improved type of neck band. When a collar of a size smaller than the size of a shirt on which it is to be worn, is being secured in position by means of buttons, the unlined flexible sections 6, are adapted to readily give way, that is flex, 70 bend or fold the necessary amount to permit the smaller collar to conveniently fit on the neck band without occasioning any uncomfortableness to the wearer. It will thus be seen that a shirt with an improved neck or 75 collar band of the kind described, is adapted to permit collars of sizes smaller and larger than the size of the shirt to be worn therewith, thereby permitting haberdashers to 80 reduce their stock materially and still be able to supply the wants of their trade.

I am aware that numerous details of construction may be varied through a wide range without departing from the principles of this invention, and I therefore do not 85 purpose limiting the patent granted otherwise than necessitated by the prior art.

I claim as my invention:—

1. A neck band comprising an outside surface ply, an inside surface ply and reinforcing material between said plies, the reinforcing material being in several pieces, the total length of which is less than the length 90 of the neck band and means for fastening these pieces in place, whereby separated portions of the neck band are left without reinforcement.

2. A neck band comprising an outside surface ply, an inside surface ply and reinforcing material between said plies, the reinforcing material being in several pieces the total length of which is less than the length 100 of the neck band and means for fastening these pieces in place, button holes through the neckband, certain of said reinforcing 105 pieces being located at the button holes, whereby separated portions of the neck band are left without reinforcement, said non-reinforced portions being between the button holes.

In testimony whereof I have hereunto 110 subscribed my name in the presence of two subscribing witnesses.

ALEX BERNSTEIN.
